UNITED STATES PATENT OFFICE.

HENRY SCHADE, OF SHELBY, IOWA.

AIR-FED OILER.

1,236,215.

Specification of Letters Patent. Patented Aug. 7, 1917.

Application filed November 3, 1915. Serial No. 59,866.

To all whom it may concern:

Be it known that I, HENRY SCHADE, a citizen of the United States, residing at Shelby, in the county of Shelby and State 5 of Iowa, have invented certain new and useful Improvements in Air-Fed Oilers, of which the following is a specification.

The invention relates to oil cans, and more particularly to the class of air fed oilers.

10 The primary object of the invention is the provision of an oiler of this character, wherein an air pump has communication with the reservoir for containing the oil so that the latter will be under pressure, to assure 15 the positive feed thereof through the delivery spout, irrespective of the position of the oiler, thus making the same useful to machinists, engineers, or the like.

Another object of the invention is the provision 20 of an oiler of this character, wherein the feed of oil therefrom is under positive manual control, so that the desired quantity can be had, without liability of waste in the use of the oiler.

25 A further object of the invention is the provision of an oiler of this character, which is simple in construction, thoroughly reliable and efficient in operation; strong, durable, positive in action, and inexpensive in manufacture.

30 With these and other objects in view, the invention consists in the features of construction, combination and arrangement of parts as will be hereinafter fully described, 35 illustrated in the accompanying drawing, and pointed out in the claim hereunto appended.

In the accompanying drawings:—

Figure 1, is a side elevation of an oiler 40 constructed in accordance with the invention.

Fig. 2, is a top plan view thereof.

Fig. 3, is a vertical longitudinal sectional view.

45 Fig. 4, is a sectional view on the line 4—4 of Fig. 1.

Similar reference characters indicate corresponding parts throughout the several views in the drawings.

50 Referring to the drawings, in detail, A, designates the body of the oiler, which constitutes the reservoir for the oil, having at its top a delivery or discharge spout 5, tapered toward its free end and slightly 55 curved. Through this spout is delivered the oil from the reservoir, while the bottom

6 of the body, is of concavo-convex shape, and is formed with a central threaded aperture 7, providing a filling opening, the same being closed by means of a thumb screw 60 plug 8, detachably engaged in the said aperture. As is apparent when the body is inverted the arched bottom 6 serves as a funnel. Provided at the bottom 6, of the body A, is an annular base flange 9, which permits the oiler being brought to rest without interference by the plug when the said oiler is not in use.

Diametrically opposite the spout 5, spaced from the body A, and parallel with the vertical wall thereof is a pump barrel or cylinder 10, having at its lower end a nipple connection 11, with the body A, for communication therewith. The nipple connection is fitted interiorly thereof with a check 70 valve 12, while working within the barrel or cylinder 10, is a piston 13, the stem of which projects through a cap 14, on the barrel or cylinder and terminates in a hand knob 15, for permitting manual manipulation of the piston for forcing air under pressure into the reservoir. The valve 12, is designed to prevent back flow of the air from the reservoir to the barrel or cylinder, and in this manner the oil is put under 75 pressure for the positive feed of the same from the oiler.

Mounted upon the top of the body A, is a U-shaped bracket 16, in the limbs of which is slidably supported a spring tensioned valve operating rod 17, which is connected to the lever 18, of a cut off valve 19, arranged in the spout 5. The spring 20, which tensions the rod 17, has one end bearing against one limb of the bracket 16, 25 and its other end bearing against a shoulder 21, on the rod 17, to act thereon for holding the valve 19, normally closed, and thereby to shut off the delivery of oil from the reservoir. On pressing upon the rod 17, 100 however, the valve 19, can be opened to the proper extent to regulate the feed of oil from the reservoir for oiling purposes during the use of the oiler. A collar 22, is integral with the rod 17 and is normally held 105 in abutting relation with one of the limbs of the bracket 16 to limit the movement of the rod and consequently maintain the valve 19 in a closed position.

From the foregoing it is thought that the 110 construction and manner of operation of the oiler will be clearly understood, and there-

fore a more extended explanation has been omitted.

What is claimed is:

In a device of the kind described, in combination a cylinder, a pipe projecting through the top of the cylinder into the cylinder toward its bottom, the upper end of said pipe being curved forwardly, a valve casting on said pipe above the top of said cylinder, a rotatable plug in said casting, an arm secured to said plug, a U-shaped bracket secured to the top of said cylinder and having its opposite lugs inclined upwardly, openings formed in the respective lugs, the opening of one lug being disposed in a higher plane than the opening in the other lug, a valve operating rod slidably

mounted in the lugs of said U-shaped bracket, a fixed collar on said rod engaging one side of said lugs to hold said rod 20 against movement in one direction, a second fixed collar on said rod spaced from the opposite side of said last named lug, a spring coiled around said rod and bearing at one end against said last named lug and against 25 said secured collar, and a push head formed terminally on said rod, said rod being pivotally secured to the free end of said arm so as to normally hold this arm inclined up- 30 wardly so that said arm may move upwardly toward the upper dead center position of said arm.

In testimony whereof I affix my signature.

HENRY SCHADE.
